METHOD AND APPARATUS FOR STORING
ICE CUBESCharles E. Gerhard, Glenilde, Pa., assignor to
Philco Corporation, Philadelphia, Pa., a corpora-
tion of Pennsylvania

Application May 2, 1941, Serial No. 391,607

3 Claims. (Cl. 62—108.5)

This invention relates to the storage of pre-frozen ice cubes or foods in a domestic refrigerator, and more particularly to a novel method of and apparatus for storing individual cubes at sub-freezing temperatures:

Users of domestic refrigerators of the mechanical type have for many years been confronted with the problem of handling ice cubes. For example, it is quite difficult, if not impossible, to remove ice cubes individually from the tray in which frozen; hence the usual practice of removing all of the ice cubes from the tray and then placing those not immediately used into the evaporator drip pan or other dish within the refrigerator food storage compartment. This practice leads to further difficulties and objections for the cubes thus stored in the drip pan or other dish become frozen together and to said pan or dish thereby requiring that the individual cubes be broken apart forcibly from each other and from the pan or dish when it is desired to use them.

Thus an arrangement in mechanical domestic refrigerators which permits of easy removal of one or more individual ice cubes without the use of any mechanical aid, and preferably without the necessity for removing the ice cube tray from the refrigerator, has long been desired and sought after.

With this in mind, the present invention provides a novel, convenient and easily usable arrangement that entirely eliminates the foregoing difficulties and objections, and the principal object of the invention is to provide, in a mechanical domestic refrigerator, a novel method and apparatus whereby pre-frozen ice cubes can be stored and kept frozen without becoming frozen together or to a container thereby making individual ice cubes readily obtainable for use as desired.

Another object of the present invention is to provide a novel method for producing and obtaining in a domestic refrigerator readily available individual ice cubes.

A further object of the invention is to provide a novel method for storing ice cubes within the freezing unit of a domestic refrigerator.

Still a further object of the invention is to provide a novel device or apparatus for the storage of individual ice cubes in domestic refrigeration apparatus.

These and other objects of the invention and the various features and details thereof are hereinafter fully set forth and described and shown in the accompanying drawing in which:

Figure 1 is a front view in perspective of a domestic refrigerator; and

Figure 2 is a view in perspective of apparatus constructed in accordance with this invention and for practicing the method thereof.

Referring now more particularly to the drawing, reference numeral 1 designates generally a mechanical domestic refrigerator having therein a food storage compartment 2 provided, in the present illustration, with the usual shelves 3.

Located in the upper portion of the food storage compartment 2 is a cooling unit 4 which is normally of the refrigerant evaporator type through which a refrigerant is circulated by suitable mechanism such as, for example, a motor driven compressor (not shown). More particularly such a cooling unit 4 may embody the construction shown and described in the co-pending application of Malcolm G. Shoemaker, Serial No. 335,579, filed May 16, 1940, and may be divided by a vertical partition into two laterally adjacent chambers 6 and 7, the latter of which preferably is closed except at the front by walls of the cooling unit. Of course, the chamber 6 may be similarly closed if desired.

As shown in Figure 1, the front openings of the chambers 6 and 7 of the cooling unit 4 preferably are closed by means of doors or other suitable closures 8 and 9 respectively, which form, together with the walls of the unit 4, a substantially closed chamber 7 or chambers 6 and 7, as the case may be. Disposed beneath the unit 4 is a baffle member (not visible) which may be constructed and arranged to direct the flow of air within the refrigerator about and into contact with said unit 4 thereby cooling the food storage compartment 2 in the manner shown and described, for example, in the copending application of Frank D. Peltier, Serial No. 347,526, filed July 25, 1940, now Patent No. 2,297,581.

By employing a construction similar to that hereinabove referred to, the air circulating within the food storage compartment 2 contacts only the exterior surfaces of the walls of the cooling unit 4 that enclose the chamber 7 for since the latter is entirely closed, substantially none of the circulating air can enter said chamber 7. Hence no moisture from the food storage compartment 2 is conveyed into the chamber 7 and any small amount of moisture initially within said chamber will be condensed on the interior wall surfaces thereof with the result that the interior of the chamber 7 will be very dry.

Now the cooling unit 4 of the refrigerator is preferably maintained at a temperature of about

10° F., and the present invention involves, essentially, the discovery that by placing separated pre-frozen individual ice cubes in a container supported in a dry sub-freezing atmosphere such as exists in the chamber 7 of said cooling unit, the said ice cubes can be prevented from freezing together and to the container provided the latter is supported in said chamber free from thermal conductive contact with the refrigerated walls thereof. Thus the ice cubes can be easily removed from the container individually for use as desired.

To this end the present invention comprehends the provision of a suitable rack or the like 10 for supporting one or more containers 11 within the chamber 7 of the unit 4 in the manner set forth. Preferably, the containers 11 are conventional ice cube freezing trays for use with which there are provided the usual cube partitioning grids (not shown), for example, constructed according to the disclosure in United States Patent No. 2,199,740, issued May 7, 1940.

The rack or like structure 10 is shown in Figure 2 of the drawing and comprises vertical front and rear end brackets 12 and 13 respectively connected together at their opposite sides by one or more longitudinal rails 14 on which ice trays 11 are intended to be supported in the manner illustrated. For the purpose of supporting the rack 10 free from thermal conductive contact with the cooling unit bottom wall on which it rests, the bottom end portions of the legs of the end brackets 12 and 13 have secured thereon members or feet 15 of suitable thermal insulating material such as, for example, rubber, Bakelite, plastic or the like, as shown in Figure 2.

In practicing the present invention, the ice trays 11 with their cube partitioning grids in place are filled with water and placed within the chamber 6 of the cooling unit 4 to be frozen into ice cubes in the conventional manner. After the water has been frozen into ice cubes the trays 11 are removed from the compartment 6 and the cubes then broken loose from the partitioning grid, from the trays 10, and from each other by any one of the mechanical methods generally in use. The grid is then removed leaving the individual dry ice cubes in spaced and separated relation to each other within their tray.

A tray 11 containing ice cubes in such separated arrangement is then placed within the cooling unit chamber 7 upon the support or rack 10 therein and the very dry sub-freezing atmosphere maintained within said chamber 7 will keep the cubes in a frozen state and at the same time prevent the formation of a new or fresh ice bond between adjacent cubes and between the cubes and the walls of the tray 11 due to the absence of moisture within the chamber which otherwise would condense upon the cubes or the trays. Hence, the ice cubes remain separated and can be easily removed individually from the trays as desired for use.

This novel result is achieved principally because the feet 15 of insulating material on the rack 10 provide a thermal break in the contact between the cooling unit 4 and said rack 10 with the result that the latter and the trays 11 are not cooled by direct conduction from the unit 4. Rather, the trays 11 and their ice cubes are cooled solely by convection by the air and thus are maintained substantially at the temperature of the air within the unit chamber 7. The temperature

of the air in chamber 7 is always slightly above the temperature of the walls of the cooling unit 4 and, hence, any moisture in the air in said chamber will condense on the surface of the cooler walls of said unit 4 and not upon the slightly warmer surfaces of the ice cubes or trays 11. Thus by maintaining the cubes and trays at the same temperature and free from the condensation of moisture thereon, the said cubes will neither adhere to each other or to the tray nor can a new or fresh ice bond between them be formed.

From the foregoing it will be seen that the present invention provides a novel method and apparatus for storing separated, pre-frozen, individual ice cubes in a domestic refrigerator in such a manner that the stored ice cubes will be prevented from freezing to one another and to their container and will remain separated so that individual cubes can be easily removed for use as desired.

While a particular embodiment of the present invention has herein been illustrated and described, it is not intended that the invention be limited to such disclosure but that changes and modifications may be made and incorporated therein as desired, within the scope of the annexed claims.

I claim:

1. The method of making and storing individual ice cubes in a domestic refrigerator which comprises freezing water in a container to form a plurality of individual ice cubes, breaking the ice bond between said ice cubes and between the ice cubes and said container to separate said cubes from each other and the container, and then placing said container with the separated cubes therein upon a support located in and insulated from thermal conductive contact with a freezing chamber having a very low moisture content thereby to prevent said cubes from freezing to one another and to the container so that the individual cubes can be readily and easily removed for use as desired.

2. Apparatus for storing individual ice cubes within a domestic refrigerator comprising a metallic refrigerant evaporator having therein a storage compartment, means substantially closing said compartment against the entrance of air and moisture, and means for supporting an ice cube container within said evaporator storage compartment free from thermal conductive contact with the evaporator comprising a rack having legs provided with feet of thermally non-conductive material arranged to contact and rest upon the bottom wall of said evaporator storage compartment so that said ice cube container is cooled solely by convection of air within the storage compartment.

3. Apparatus for storing individual ice cubes within a domestic refrigerator comprising a metallic refrigerant evaporator having therein a storage compartment, means substantially enclosing said compartment against the entrance of air and moisture, and means for supporting an ice cube container within said evaporator storage compartment free from thermal conductive contact with the evaporator, said last means comprising a rack at least a portion of which is of non-conductive material arranged to provide a thermal break between said container and said evaporator storage compartment.

CHARLES E. GERHARD.
